UNITED STATES PATENT OFFICE.

LEWIS A. GRISWOLD, OF DAYTON, OHIO.

GARMENT-SUPPORTER.

1,196,678.

Specification of Letters Patent. Patented Aug. 29, 1916.

Application filed February 26, 1916. Serial No. 80,700.

To all whom it may concern:

Be it known that I, LEWIS A. GRISWOLD, a citizen of the United States, residing at Dayton, in the county of Montgomery and State of Ohio, have invented new and useful Improvements in Garment-Supporters, of which the following is a specification.

This invention is an improved garment supporter especially adapted for holding trousers and drawers with their waist bands in desired relative position, the object of the invention being to provide improved devices of this kind which are cheap and simple in construction, and which accommodate themselves to the movements of the wearer and serve to greatly promote the comfort of the wearer and prevent the garments from bagging or chafing.

The invention consists in the construction, combination, and arrangement of devices hereinafter described and claimed.

In the accompanying drawing:—Figure 1 is an elevation of garment supporting devices constructed and arranged in accordance with my invention and showing the same connected to one end of the shoulder strap. Fig. 2 is a detail sectional view of the same on the plane indicated on the line *a—a* of Fig. 1.

In the embodiment of my invention the shoulder strap 1 is doubled at the end as at 2 and provided with a suitable clasp or adjusting buckle 3. A link ring 4 is attached by the loop thus formed to the end of the suspender or shoulder strap. A cast off loop 5, which has a suitable snap fastener or other suitable fastener 6 is attached to the link ring and is also detachably connected to a link 7. An equalizing strap 8 is slidably engaged with the link 7 and hence is con-

nected to the suspender strap. Links 9 are attached to the ends of the equalizing strap and end straps 10, which have button holes 11, are slidably engaged with the said links. One of said end straps is to be buttoned to the waist band of the trousers and the other is to be buttoned to the waist band of the drawers. Owing to the slideable connection of the equalizing strap to the suspender strap, said equalizing strap coacts with the end straps in automatically adjusting the waist bands of the garments and serves to hold them in the desired relative position and hence prevents bagging or chafing of the garments. The equalizing straps of the suspenders slide back and forth through the links 7 so that the supporters accommodate themselves to the movements of the wearer and greatly promote his comfort. The end straps also move slideably in the links 9 and serve to adjust themselves to the position of the garments and to relieve strain on the buttons and on the garments.

Other changes may also be made within the scope of my invention as defined in the appended claim.

Having thus described my invention what I claim is:—

In a garment supporter, a shoulder strap; an equalizing strap slidably connected solely to the said shoulder strap, and end straps each slidably connected to one end of the equalizing strap.

In testimony whereof I affix my signature in presence of two witnesses.

LEWIS A. GRISWOLD.
